UNITED STATES PATENT OFFICE.

ALLAN P. LINDBLAD, OF EVERETT, MASSACHUSETTS.

DESIGN FOR A COMBINATION PAPER NAPKIN AND MENU-CARD HOLDER.

Application filed April 22, 1926. Serial No. 17,396. Term of patent 14 years.

To all whom it may concern:

Be it known that I, ALLAN P. LINDBLAD, a citizen of the United States, residing at Everett, in the county of Middlesex and State of Massachusetts, have invented a new, original, and ornamental Design for Combination Paper Napkin and Menu-Card Holder, of which the following is a specification, reference being had to the accompanying drawing, forming a part thereof.

The figure is a perspective view of a combination paper napkin and menu-card holder, showing my new design.

I claim:

The ornamental design for a combination paper napkin and menu-card holder, as shown.

In testimony whereof I have affixed my signature.

ALLAN P. LINDBLAD.
